CLAIM

The ornamental design for pet treat protective housing, as shown and described.

DESCRIPTION

FIG. 1 is a front perspective view of an illustrative embodiment of the pet treat protective housing;

FIG. 2 is a front view of the pet treat protective housing in FIG. 1;

FIG. 3 is a rear view of the pet treat protective housing in FIGS. 1-2;

FIG. 4 is a right side view of the pet treat protective housing in FIGS. 1-3;

FIG. 5 is a left view of the pet treat protective housing in FIGS. 1-4;

FIG. 6 is a top view of the pet treat protective housing in FIGS. 1-5;

FIG. 7 is a bottom view of the pet treat protective housing in FIGS. 1-6;

FIG. 8 is an exploded perspective view of the pet treat protective housing in FIGS. 1-7; and,

FIG. 9 is an environmental perspective view of the pet treat protective housing in FIGS. 1-7.

The broken lines are for illustration only and form no part of the claimed design.
